UNITED STATES PATENT OFFICE.

HARRY LAWRIE, OF OMAHA, NEBRASKA.

WATER-HEATING ATTACHMENT FOR FURNACES.

1,026,753.

Specification of Letters Patent.

Patented May 21, 1912.

Application filed December 12, 1911. Serial No. 665,384.

To all whom it may concern:

Be it known that I, HARRY LAWRIE, a citizen of the United States, and a resident of Omaha, in the county of Douglas and 5 State of Nebraska, have invented certain new and useful Improvements in Water-Heating Attachments for Furnaces, of which the following is a specification.

My invention relates to furnaces of the 10 kinds used in heating dwellings, and especially to water-heating appliances used in connection with such furnaces.

It is the object of my invention to provide in connection with furnaces of this type an 15 auxiliary water-heating means arranged so that it will not interfere with the firing, cleaning or drafts of the furnace, and of which the interior of the heating device is readily accessible so that accumulations of 20 sediment or scale may be removed therefrom.

A further object of my invention is to enable the cleaning out of the auxiliary water-heater without disturbing or disconnecting 25 the piping leading thereto.

In the accompanying drawings, Figure 1 is a partial vertical sectional view of a water-heating furnace having my auxiliary heating means applied thereto, Fig. 2 is a 30 detail horizontal sectional view of the same, the section being on the plane of the line $x-x$ of Fig. 1, and Fig. 3 is a rear elevation thereof with the cover-plate of the auxiliary heating chamber removed.

It may be noted that with air-heating furnaces, water-heating furnaces and low-pressure steam furnaces as ordinarily used in 35 dwellings, when it is desired to also heat water for bathing, kitchen, laundry or similar purposes, it is customary to extend a coil or loop of pipe into the combustion chamber of the furnace, connecting said coil with a storage tank so that a circulation of water may occur between the tank and heating- 40 coil, the tank also being connected with the cold-water supply of the house and with the taps from which the hot water is to be drawn. When such a coil or loop of pipe is placed in the combustion chamber of the 45 furnace it usually interferes with the firing and cleaning of the furnace and frequently is necessarily so placed that it interferes with the drafts. In localities where the 50 water supply contains any appreciable quantity of mineral matter held in solution, such mineral matter is deposited as a hard scale

on the inside of the heating coil. This scale, being a poor conductor of heat, interferes with the absorption of heat by the water in the coil and, by continued accumulation, may 50 even entirely close the opening through the coil so that it will be burned out, or, if water is confined therein, cause an explosion. It is usually impracticable, if not impossible, to clean the scale out of heating coils of this 55 kind, and the remedy ordinarily employed is to remove the coil and replace it with a new one. My invention obviates all of the above difficulties.

In the accompanying drawings my invention is shown as applied to a sectional cast-metal water-heating furnace of an ordinary type in which the lower or base section 1 forms the ash-pit and is provided with the usual ash-pit door 2 and draft-door 3. The 75 section 4 which is disposed above the section 1, has at the bottom the grate 5 and at one side thereof the fuel door 6. The section 4 and the succeeding superposed sections 7 are formed with communicating 80 water-spaces 8 therein, through which is circulated the water used in the radiators with which the furnace is connected, and the sections 7 are also formed with suitable passages 9 through them for the circulation of 85 the combustion products passing from the fuel and combustion chamber 10 of which the section 4 forms the inclosing casing.

In the side of the section 4 opposite the fuel door 6 is formed the auxiliary water-heating chamber 11 of which the outer side is closed by a cover-plate 12 removably secured thereon by screws 13. With the exception of the cover-plate 12 the walls of the chamber 11 are formed integrally with the 95 walls of the fuel and combustion chamber 10, and, preferably, there are several integral flanges 14 extended from the inner wall of the chamber out to the cover-plate. Said flanges 14 are stopped off to form vertical 100 openings past them at alternate ends thereof, as shown in Fig. 3. At the outer side of the chamber 11 and at one end thereof is an overhanging flange 15 into which are screwed the supply and outlet pipes 16 and 105 17 which extend to the usual hot-water tank or reservoir. The flanges 14 serve as baffle-plates to direct the circulation of water through the heating chamber, and also, being integral with the wall of the chamber 110 which adjoins the fuel and combustion chamber of the furnace, serve to materially

increase the radiating surface available for heating the water which is circulated through the chamber.

It will be obvious that, by the construction shown, a supply of water for washing and similar purposes may be effectively heated without interfering with the firing, cleaning or the drafts of the furnace. It will also be apparent that any sediment or scale which may accumulate in the chamber 11 may be readily removed after taking off the cover-plate 12, as shown in Fig. 3, and that the removal of the cover-plate does not necessitate the disconnecting of the pipes 16 15 and 17.

Now, having described my invention, what I claim and desire to secure by Letters Patent, is:

1. The combination with a cast-metal heating furnace, of an auxiliary water-heater comprising means integral with the walls of the fuel and combustion chamber and forming a heating chamber adjoining the same, water pipes connecting with said auxiliary heater chamber, and an external removable cover-plate for said heater chamber.

2. The combination with a heating furnace having a cast-metal casing inclosing a combustion chamber and a main water-heating chamber, of a casing integral with the first and inclosing an auxiliary water-heating chamber separate from the main water-heating chamber, and water supply and outlet pipes connected with said auxiliary water-heating chamber.

3. In a furnace, the combination with a metal casing inclosing a combustion chamber and a main heating chamber, of a casing formed integrally therewith and inclosing an auxiliary water-heating chamber adjoining the combustion chamber, supply and outlet pipes connected with the latter casing,

and flanges extending into the latter chamber from the wall thereof adjoining the combustion chamber.

4. The combination with a cast-metal heating furnace, of a metal casing having one side thereof adjoining the combustion chamber of the furnace, a removable cover-plate at the outer side of the casing, water supply and outlet pipes connected with the casing, and flanges extending across the casing from the wall thereof adjoining the combustion chamber, said flanges being arranged to form a passage through the casing from the supply pipe to the outlet pipe.

5. In a furnace, a casing inclosing a combustion chamber and a main heating chamber, a casing integral with the first and inclosing a water-chamber separated from the combustion chamber by a single wall, a removable cover-plate forming the outer wall of the water-chamber, and flanges extending from the wall of the combustion chamber into the water chamber.

6. In a furnace, an integral metal casing inclosing a combustion chamber, a main heating chamber and an auxiliary water-chamber of which the inner wall is coincident with the wall of the combustion chamber, a removable cover-plate forming the outer wall of the water-chamber, water supply and outlet pipes connected with the water-chamber casing, and flanges integral with and extending from the inner wall of the water-chamber to the cover-plate, said flanges being adapted to direct water from the supply pipe to all parts of the chamber to the outlet pipe.

In testimony whereof I have hereunto subscribed my name in the presence of two witnesses.

HARRY LAWRIE.
